US0D1026977S

(12) **United States Design Patent** (10) Patent No.: **US D1,026,977 S**
(45) Date of Patent: ** May 14, 2024

(54) **TISSUE MACHINE**

(71) Applicant: **Valmet Aktiebolag**, Sundsvall (SE)

(72) Inventors: **Stefan Söderberg**, Forshaga (SE); **Karl Adamsson**, Skoghall (SE); **Stefan Karlsson**, Karlstad (SE)

(73) Assignee: **Valmet Aktiebolag**, Stokholm (SE)

(**) Term: **15 Years**

(21) Appl. No.: **35/512,308**

(22) Filed: **Jan. 26, 2021**

(80) **Hague Agreement Data**

Int. Filing Date: **Jan. 26, 2021**

Int. Reg. No.: **DM/212686**

Int. Reg. Date: **Jan. 26, 2021**

Int. Reg. Pub. Date: **Jul. 30, 2021**

(51) **LOC (14) Cl.** **15-09**

(52) **U.S. Cl.**

USPC **D15/122**

(58) **Field of Classification Search**

USPC D15/122, 199; 162/358.3, 358.5

CPC D21F 3/0218; D21F 3/045; D21F 3/0281;

D21F 9/003; D21F 5/181; D21F 11/006;

D21F 11/14; D21H 27/002
